UNITED STATES PATENT OFFICE.

HARRY C. FRATT, OF NORRISTOWN, PENNSYLVANIA.

REFRIGERATOR.

1,367,368.

Specification of Letters Patent. Patented Feb. 1, 1921.

Application filed May 8, 1920. Serial No. 379,833.

To all whom it may concern:

Be it known that I, HARRY C. FRATT, a citizen of the United States, residing at Norristown, in the county of Montgomery and State of Pennsylvania, have invented new and useful Improvements in Refrigerators, of which the following is a specification.

This invention relates to refrigerators, and has for its primary object the provision of means to eliminate the accumulation of moisture within the outer casing and affecting the packing therein and thus maintain the latter in a clean and sweet condition.

Objectionable odors which are frequently found in refrigerators, are caused by the accumulation of moisture in the outer casing of the refrigerator, this moisture saturating the packing in said outer casing and keeping the latter in a very unsanitary condition. The disposition of the packing is such that access cannot be readily had to the same, and consequently in due course of time this packing throws off an odor which is very objectionable. Cleaning of the interior of the refrigerator does not destroy the odor which as above stated is emitted from the packing in the outer casing.

In carrying out the invention, I line the interior of the outer casing with metal or other suitable material which prevents the moisture from gaining access to the packing, and space the inner casing from said lining, thus defining a dead air chamber between the inner and outer casings, which chamber tends to dry the moisture which enters the chamber from the inner casing.

Another object of importance resides in the construction of a refrigerator having normally closed openings in the top and front wall thereof, which permits the air chamber to be properly cleaned when desired.

The nature and advantages of the invention will be better understood when the following detailed description is read in connection with the accompanying drawing, the invention residing in the construction, combination and arrangement of parts as claimed.

In the drawing forming part of the application, like numerals of reference indicate similar parts in the several views, and wherein:

Figure 1 is a vertical sectional view of a

refrigerator constructed in accordance with my invention.

Fig. 2 is a horizontal sectional view therethrough.

Fig. 3 is a fragmentary front elevation.

Fig. 4 is a sectional view through the top wall thereof.

Referring to the drawing in detail, the refrigerator is indicated generally at A, and includes an outer casing 10 and an inner casing 11. The outer casing is lined with metal or other suitable material which will prevent moisture from gaining access through the packing which as shown is interposed between the lining 12 and the outer casing, the packing being indicated at 13. The inner casing 11 may be of any suitable construction and design, but in accordance with my invention is spaced from the lining 12, the intervening space between the inner casing 11 and the lining 12 defining a dead air chamber which tends to dry the moisture which enters the space or chamber 14 from the inner casing 11. Consequently, the packing 13 cannot be affected by moisture which passes through the wall of the inner casing 11, and which fact serves to maintain not only the packing 13 but the refrigerator in its entirety in a sweet and clean condition.

For the purpose of gaining access to the chamber 14, when it is desired to cleanse the latter, I preferably provide the top wall of the refrigerator with an opening 16 which is normally sealed by the closure 17, the front wall being also provided with an opening 18 normally sealed by the closure 19. The opening 16 is of a size to permit the insertion of a hose or the like to introduce water or any other cleaning agent into the chamber 14 at the top thereof, so that the interior of the chamber may be properly cleaned, the water or cleaning agent passing out through the opening 18.

While it is believed that from the foregoing description the nature and advantages of the invention will be readily apparent, I desire to have it understood that I do not limit myself to the details herein shown and described, and that such changes may be resorted to when desired as fall within the scope of what is claimed.

What I claim is:

A refrigerator comprising spaced inner and outer casings, a metallic lining for the

outer casing, the lining being spaced from the walls of the inner and outer casings and defining an air chamber between the same and the casing, packing interposed between 5 the lining and the wall of the outer casing, the top of the refrigerator having an opening communicating with said air chamber, a

plug removably fitted in said opening, the front wall of the refrigerator having an elongated opening communicating with the 10 said air chamber, and a closure for the latter mentioned opening.

In testimony whereof I affix my signature.
HARRY C. FRATT.
